UNITED STATES PATENT OFFICE.

ERNEST DALTROFF, OF PARIS, FRANCE, ASSIGNOR TO CARON CORPORATION, OF NEW YORK, N. Y., A CORPORATION OF NEW YORK.

DESIGN FOR A BOX.

Application filed January 31, 1924. Serial No. 8,493. Term of patent 14 years.

To all whom it may concern:

Be it known that I, ERNEST DALTROFF, a citizen of the Republic of France, residing in the city of Paris, République of France, have invented a new, original, and ornamental Design for a Box, of which the following is a specification, reference being had to the accompanying drawing, forming a part thereof.

In the drawings,

I claim:—

The ornamental design for a box substantially as shown.

ERNEST DALTROFF.
